RAILWAY TRAFFIC CONTROLLING APPARATUS

Harry C. Vantassel, Swissvale, Pa., assignor to
The Union Switch & Signal Company, Swiss-
vale, Pa., a corporation of Pennsylvania

Application April 14, 1936, Serial No. 74,256

9 Claims. (Cl. 246—134)

My invention relates to railway traffic controlling apparatus, and particularly to apparatus for preventing improper operation of a plurality of manually operable track switches which are all located in the same track section.

I will describe three forms of apparatus embodying my invention, and will then point out the novel features thereof in claims.

In the accompanying drawings, Fig. 1 is a diagrammatic view showing one form of apparatus embodying my invention. Fig. 2 is a diagrammatic view showing another form of apparatus embodying my invention. Fig. 3 is a view similar to Fig. 2 showing a modification of the apparatus illustrated in Fig. 2.

Similar reference characters refer to similar parts in each of the several views.

Referring first to Fig. 1, the reference characters 1 and 1^a designate the track rails of a stretch A of railway track over which traffic normally moves from left to right. The rails 1 and 1^a are divided, by means of insulated joints 2, to form a plurality of track sections only one of which B—C is shown complete in the drawings. Each track section is provided with a track circuit including a battery 3 connected across the rails adjacent one end of the section, and a track relay, designated by the reference character R with a distinguishing exponent, connected across the rails adjacent the other end of the section. Traffic entering each track section is governed by a signal S which may be of any suitable type, but which, in the form here shown, is a two-position semaphore signal capable of indicating proceed or stop according as the signal is energized or deenergized.

Located in section B—C are a plurality of manually operable track switches S¹, S², and S³ which connect this section with a plurality of spurs or sidings D¹, D², and D³, respectively. Each siding is insulated from section B—C by means of two sets of insulated joints 2, and the rails of each siding between the pairs of joints are cross-bonded with the rails of section B—C in the usual and well-known manner. The means for manually operating the switches S¹, S², and S³ may be of any suitable type, but inasmuch as these means form no part of my present invention, they are omitted from the drawings for the sake of simplicity.

Associated with each switch S is a relay designated by the reference character E with a distinguishing exponent; a switch operated contact designated by the reference character F with a distinguishing exponent, and arranged to be

closed or open according as the associated switch occupies its normal or reverse position; a time release designated by the reference character TR with a distinguishing exponent; a push button designated by the reference character P with a distinguishing exponent; and two indication devices designated by the reference characters G and W, respectively, with suitable distinguishing exponents.

The time releases TR may be of any desired type but as here shown each time release is a clockwork time release similar to that shown and described in Letters Patent of the United States No. 1,989,522, granted to W. C. McWhirter, on Jan. 29, 1935, for Time governed circuit controlling mechanism. Since the time releases TR are similar to the time release shown in the said McWhirter patent, it is believed that for purposes of the present disclosure it is sufficient to state that each of these time releases comprises two normally closed contacts 4 and 5 which become opened immediately when the time release is set into operation, and a normally open contact 6 which becomes closed at the expiration of a predetermined time interval after the time release is set into operation. After a time release has been operated to open its contacts 4 and 5 and to close its contact 6, the contacts 4 and 5 will subsequently remain open and the contact 6 will remain closed until the time release is manually restored to its normal condition.

Each relay E is provided with a pickup circuit which is controlled by the associated push button P, by the other two relays E, and by the two track relays R^B and R^C. The pickup circuit for relay E¹ passes from terminal BX of a suitable source of current, not shown in the drawings, through front contact 7 of track relay R^B, line wire 8, front contact 9 of track relay R^C, wire 10, back contact 11—11^a of relay E³, wire 12, back contact 11—11^a of relay E², wire 14, push button P¹, and the winding of relay E¹ to the other terminal CX of the source. The pickup circuit for relay E² passes from terminal BX of the source through front contact 7 of track relay R^B, wire 8, front contact 9 of track relay R^C, wire 10, back contact 11—11^a of relay E³, wire 12, push button P², the winding of relay E², wires 15 and 16, and back contact 17 of relay E¹ to terminal CX of the source. The pickup circuit for relay E³ passes from terminal BX of the source through front contact 7 of relay R^B, wire 8, front contact 9 of track relay R^C, wire 10, push button P³, wires 18 and 19, back contact 17 of relay E², wire 16, and back contact 17 of relay E¹ to terminal CX.

Each relay E is also provided with a stick circuit which is similar to its pickup circuit with the exception that the stick circuit includes the front contact 11-11^b of the relay in place of the associated push button P.

It will be seen, therefore, that if the push button P associated with one of the relays E is depressed, it will complete the pickup circuit for the associated relay E provided the other two relays E are both deenergized and section B-C and the section to the left of section B-C are both unoccupied. It will also be seen that when one of the relays E becomes energized, the resultant closing of its front contact 11-11^b will complete the stick circuit for the relay, and the relay will, therefore, subsequently remain energized until a train enters section B-C or the section to the left of this section and deenergizes the associated track relay. It will further be seen that since the pickup circuit for each of the relays E can only become closed when the two remaining relays E are deenergized, the energization of any one of the relays E will prevent the other two relays E from becoming energized until after such energized relay subsequently becomes deenergized.

The indication devices G and W, which indication devices are here shown as electric lamps, are each connected in multiple with the associated relay E over the contacts 5 and 6, respectively, of the associated time release TR. It will be seen, therefore, that when either the pickup or stick circuit for one of the relays E is closed, the associated lamp G or W will be energized according as the contact 5 or the contact 6 of the associated clockwork time release is then closed.

The signal S^B is controlled by a signal control relay SC over a circuit which is obvious from an inspection of the drawings, and the signal control relay SC, in turn, is controlled by the relays E, by the switch operated contacts F, by the contact 4 of each of the time releases TR, and by track relay R^C over a circuit which passes from terminal BX of the source through front contact 20 of the associated track relay RC, switch operated contact F³, contact 4 of time release TR³, back contact 21 of relay E³, switch operated contact F², contact 4 of time release TR², back contact 21 of relay E², switch operated contact F¹, contact 4 of time release TR¹, back contact 21 of relay E¹, and the winding of relay SC to terminal CX of the source. It will be apparent, therefore, that signal S^B will indicate proceed or stop according as signal control relay SC is energized or deenergized, and that relay SC will be energized when and only when the relays E are all energized, the switches S all occupy their normal positions, the contact 4 of each of the time releases TR is closed, and section B-C is unoccupied.

As shown in the drawings, all parts are in their normal positions. That is to say, section B-C and the section to the left of this section are both unoccupied, so that track relays R^C and R^B are both energized, the switches S all occupy their normal positions, the switch operated contacts F are all closed, the relays E are all deenergized, the time releases TR all occupy their normal positions, the indication lamps G and W are all extinguished, signal control relay SC is energized, and signal S^B occupies its proceed position.

In explaining the operation of the apparatus as a whole, I will assume that siding D¹ is occupied by a train, and that it is desired to move this train out of the siding into section B-C. To do this, the trainman depresses push button P¹, whereupon if relays E² and E³ are both deener-

gized and section B-C and the section to the left of this section are both unoccupied, relay E¹ will immediately pick up and lamp G¹ will become lighted. If, however, either relay E² or relay E³ is energized, or if section B-C or the section to the left of section B-C is unoccupied, relay E¹ will remain deenergized and lamp G¹ will remain dark. Assuming that relay E¹ does pick up and lamp G¹ becomes lighted, the trainman is informed by the lighting of the lamp that section B-C and the section to the left of this section is unoccupied and he will then operate time release TR¹. The operation of this time release will immediately interrupt the circuit which was previously closed for lamp G¹ whereupon this lamp will become deenergized, and if, when contact 6 of time release TR¹ becomes closed, no train has entered the section to the left of section B-C, lamp W¹ will become lighted. The time required for contact 6 of time release TR¹ to close is so chosen that if a train is approaching the section to the left of section B-C within a distance which is less than braking distance, the train will have entered the section before contact 6 becomes closed in which event track relay R^C will become deenergized and will interrupt the circuit that was previously closed for relay E¹, thus deenergizing this relay and hence preventing the lamp W¹ from becoming lighted. If lamp W¹ does become lighted, the operator knows that it is safe to reverse the switch E¹, and he then does so. As soon as the train moves out of the siding D¹ and into section B-C, the resultant deenergization of track relay R^C interrupts the stick circuit for relay E¹ and thus causes this relay to become deenergized, and when the train has completely departed from section B-C, the operator restores the switch S¹ to its normal position. He also restores time release TR¹ to its normal position. The picking up of relay E¹ in response to the operation of push button P¹, of course, deenergizes signal control relay SC and causes signal S^B to move to its stop position, so that if a train enters the section to the left of point B after lamp W¹ has become lighted, the train will be compelled to stop when it reaches section B-C. After the train which moved out of the siding D¹ has departed from section B-C if the section to the left of point B is still unoccupied, all parts will become restored to their normal positions in which they are shown in the drawings. It should be noted that if the trainman fails to restore the time release TR¹ to its normal position when he restores the switch S¹ to its normal position, signal S^B will remain at stop thus insuring that no train will enter section B-C under these conditions.

The operation of the apparatus when it is desired to bring a train out of sidings D² and D³ is similar to that just described and will be apparent from an inspection of the drawings without further detailed description. The operation of the apparatus when a train proceeds directly through section B-C, or when it is desired to move a train from section B-C into one of the sidings, will also be apparent from an inspection of the drawings without further description. It should be noted, however, that when it is desired to move a train from section B-C into a siding, it is unnecessary to operate the associated relay E in order to prevent a dangerous condition because as long as the train occupies the section, or the switch, or as long as any one of the switches S is reversed, signal S^B will occupy its stop position, and will thus prevent a following

train from entering section B-C under these conditions.

Under some conditions of operation it is considered safe to reverse a switch when section B-C and the section to the left of this section are both unoccupied regardless of whether or not a train is then approaching the section to the left of section B-C within a distance which is less than braking distance, and when this is the case the time releases TR and the lamps W may be dispensed with, each lamp G in this instance being connected directly in multiple with the associated relay E¹ in such manner that each lamp G will be energized whenever the associated relay E is energized. The operation of the apparatus as a whole when the circuits are modified in this manner will be apparent from the foregoing description without further detailed description.

If desired, the relays E¹ may be of the type which are provided with a mechanical indicator in the form of a miniature signal or the like, and when this type of relay is employed, the lamps G and W and the time releases may all be dispensed with.

Referring now to Fig. 2, the apparatus here shown includes all of the apparatus shown in Fig. 1 with the exception of the indication lamps and the time releases, and in addition, this apparatus includes three switch locks L¹, L², and L³, one of which is associated with each of the switches S¹, S², and S³, and three lock releasing subsections a¹-b¹, a²-b², and a³-b³ which are formed in the section B-C adjacent the switches S¹, S², and S³, respectively, for a purpose which will be made clear presently. The switch locks L¹, L², and L³ are all alike and a description of one will, therefore, suffice for all. Referring particularly to the lock L¹, this lock comprises a lock bar K¹ which is rigidly secured to the switch S¹ for engagement by a dog M¹, by means of which the switch may be locked in its normal position in which it is shown in the drawings. Dog M¹ is actuated by a manually operable lever H¹ which is fixed to a shaft, indicated by the broken line 25 in the drawings, and which may be rocked between normal and reverse positions, indicated by the reference characters n and r, respectively. The shaft 25 carries a plurality of contacts 26, 27, and 28 which are closed when and only when the lever H¹ occupies its normal position, and a latch segment 29. The latch segment 29 is provided with a notch 29^a, and cooperates with a latch dog 30. The latch dog 30 is controlled by a magnet G¹ in such manner that when the lever H¹ occupies its normal position in which it is shown in the drawings, and the magnet G¹ is deenergized, the latch dog 30 will drop by gravity to a position in which it enters the notch 29^a, but that, when the magnet G¹ is energized, the dog 30 will be attracted by the magnet to a position in which the dog is withdrawn from the notch 29^a. It is, of course, obvious that when the dog 30 occupies the notch 29^a, movement of lever H¹ away from its normal position is prevented, but that, when the dog 30 is withdrawn from the notch 29^a, the lever H¹ is then free to move between its two extreme positions. Operatively connected with the latch dog 30 is a contact 31 which is closed or open according as the latch dog occupies its locking or its unlocking position.

Each lock releasing subsection a-b is formed in the section B-C by means of additional insulated joints 2 which are provided in the rails

1 and 1^a, and each subsection extends from a point just in rear of the associated switch to a point which is just far enough in advance of the associated switch to permit a train to shunt the subsection after the train has cleared the switch. Each subsection is provided with a track circuit including a track battery 3 and a track relay designated by the reference character R with an exponent corresponding to the exponent for the reference character of the associated switch. The rails of section B-C on opposite sides of each subsection are connected together by suitable conductors 32 and 33 in a manner which will be readily understood from an inspection of the drawings.

The magnet G of each lock L is provided with two pickup circuits, one of which includes a front contact 34 of the associated relay E, and the other of which includes a back contact 35 of the track relay for the associated sub-section and a contact 36. The circuits for the magnets G will be obvious from an inspection of the drawings without further description. Each contact 36 is of well-known type which is operated by the door of the case in which the associated lock is located in such manner that the contact will be open when the door is closed, but will be closed whenever the door is open sufficiently to permit access to the associated lock lever H.

Relay E¹ is provided with a pickup circuit which is controlled by the push button P¹, by each of the locks L, by the relays E² and E³, and by the two track relays R^B and R^C, and which passes from terminal BX of the source through front contact 36 of track relay R^B, line wire 37, front contact 38 of track relay R^C, back contact 11-11^a of relay E³, wire 39, contact 31 of magnet G³ of lock L³, contact 27 of lever H³, wire 40, back contact 11-11^a of relay E², wire 41, back contact 31 of magnet G² of lock L², contact 28 of lever H², line wire 42, push button P¹, and the winding of relay E¹ to terminal CX.

Relay E² is provided with a pickup circuit which is controlled by the push button P², by the locks L¹ and L³, by the relays E¹ and E³, and by the track relays R^B and R^C, and which passes from terminal BX through front contact 36 of track relay R^B, wire 37, front contact 38 of track relay R^C, back contact 11-11^a of relay E³, wire 39, contact 31 of magnet G³ of lock L³, lever contact 27 of lock L³, wire 40, push button P², the winding of relay E², wire 43, contact 27 of lever H¹ of lock L¹, contact 31 of magnet G¹ of lock L¹, and back contact 44 of relay E¹ to terminal CX.

Relay E³ is provided with a pickup circuit which is controlled by push button P³, by the locks L¹ and L², by the relays E¹ and E², and by the track relays R^B and R^C, and which passes from terminal BX through front contact 36 of track relay R^B, wire 37, front contact 38 of relay R^C, push button P³, the winding of relay E³, wire 45, contact 27 of lever H² of lock L², wire 46, back contact 44 of relay E², wire 43, contact 27 of lever H¹ of lock L¹, contact 31 of magnet G¹ of lock L¹, and wire 44 to terminal CX.

Each relay E is also provided with a stick circuit which is similar to the pickup circuit traced above with the exception that this latter circuit includes front contact 11-11^b of the relay in place of the associated push button P.

It will be seen, therefore, that if it is desired to energize one of the relays E, this may be done by depressing the associated push button P providing the track section B-C and the section

to the left of this section are both unoccupied, the two remaining relays E are both energized, and the locks controlled by these relays both occupy their locking positions. It will also be apparent that when the relay E becomes energized, the closing of its front contact will complete its stick circuit, and will thus cause the relay to remain energized until a train enters either section B-C or the section to the left of this section, at which time the resultant deenergization of the track relay R^B or the track relay R^C, as the case may be, will interrupt the stick circuit for the relay, and will thus cause the relay to become deenergized.

15 Signal control relay SC is provided with a circuit which passes from terminal BX through front contact 47 of track relay R^C, front contact 48 of track relay R^C, wire 49, contact 26 of lever H³ of lock L³, wire 50, back contact 21 of relay E³, switch operated contact F³, front contact 48 of track relay R², wire 51, contact 26 of lever H² of lock L², wire 52, back contact 21 of relay E², switch operated contact F², front contact 48 of track relay R¹, wire 53, contact 26 of lever H¹ of lock L¹, wire 54, back contact 21 of relay E¹, switch operated contact F¹, and the winding of relay SC to terminal CX. It will be seen, therefore, that the signal control relay SC will be energized when and only when section B-C and each of the subsections which are located in this section are all unoccupied, and the switches S¹, S², and S³ all occupy their normal positions and are locked in these positions. The relay SC controls the signal S^B in the same manner as in Fig. 1.

In explaining the operation of the apparatus shown in Fig. 2 as a whole, I will first assume that it is desired to permit a train to enter the siding D². To do this, the engineman will move his train to the position in which the rear end of the train is past the switch, but is still effective to shunt the lock releasing subsection a²-b², and a trainman will then open the door of the cover for the lock L². When the trainman does this, since the track relay R² will then be deenergized due to the presence of the train in lock releasing section a²-b², the resultant closing of the contact 36 controlled by the door of the lock L² will complete one of the pickup circuits for the magnet G², and this magnet will, therefore, become energized, and will thus move the locking dog 30 to its unlocking position. When the locking dog reaches its unlocking position, the trainman will then move the lever H² from its normal position n to its reverse position r which movement will withdraw the dog N² from the lock bar K², thus unlocking the switch. When the switch becomes unlocked, the operator may then move it to its reverse position, thus permitting the trainman to back his train into the siding D². As soon as the train clears the fouling point, the track relay R² will become deenergized and will thus interrupt the pickup circuit which was previously closed for the magnet G². This magnet will, therefore, become deenergized, and, as a result, if the operator then restores the switch to its normal position and the lever H² to its normal position, the switch will become relocked in its normal position. It should be noted that when lever H² is moved to its reverse position, all circuits for relays E¹ and E³ are then open, so that these relays are prevented from becoming energized under these conditions. Furthermore, the circuit for signal control relay SC is open, so that signal S^B will occupy its stop position.

The operation of the apparatus when it is desired to move a train from section B-C into either of the other sidings is similar to that just described and will be apparent from an inspection of the drawings without further description. 5

I will now assume that a train has been moved into the siding D² in the manner previously described and the switch S² has been subsequently restored to its normal position and locked in this position, and that it is now desired to move the train out of the siding into the section B-C. To permit this to be done, the trainman will depress the push button P², and if section B-C and the section to the left of this section are then both unoccupied, the pickup circuit for relay E² will 15 become closed, whereupon this relay will become energized and will complete its stick circuit. The energization of relay E² will complete the pickup circuit for relay G² including front contact 34 of relay E², and magnet G² will, therefore, become energized and will unlock the lever H². As soon as this lever becomes unlocked, the operator will then move the lever from its normal to its reverse position to unlock the switch in the manner previously described, and after the switch 20 has become unlocked, he will then move the switch from its normal position to its reverse position. With the switch in its reverse position, the train may then proceed into section B-C. As soon as the train passes beyond the subsection 30 a²-b², the resultant deenergization of track relay R^C will interrupt the stick circuit for relay E², and relay E² will, therefore, become deenergized. Magnet G², however, will remain energized until the train has passed completely out of 35 the subsection a²-b² by virtue of the pickup circuit for magnet G² including back contact 35 of relay R² and the associated door contact 36. As soon, however, as the train has cleared the subsection a²-b², magnet G² will then become 40 deenergized, and, as a result, if the operator then restores the switch to its normal position and the lever H² to its normal position, the switch will become relocked in its normal position in an obvious manner. When the train has passed 45 completely out of section B-C, all parts will then be restored to their normal positions in which they are shown in the drawings. It should be noted that as long as switch S² occupies its reverse position, the circuit for signal control relay 50 SC will be open at the switch operated contact F², thus insuring that signal S^B will remain in its stop position under these conditions. It will also be noted that when the train occupies either subsection a²-b² or section B-C, the circuit for 55 relay SC will also be open, and it follows, therefore, that under no conditions will a dangerous condition exist due to a movement of a train into or out of the siding D².

The operation of the apparatus shown in Fig. 2 when it is desired to move a train out of the sidings D¹ and D³ is similar to that just described and will be apparent from an inspection of the drawings without further description. 60

Referring now to Fig. 3, as here shown, the push buttons P shown in Fig. 2 have each been replaced by an associated door operated contact 56 connected in series with the contact 6 of an associated time release TR. The door operated contacts 56 are each similar to the associated 70 door operated contact 36 while the time releases TR are each similar to the time releases shown in Fig. 1. Furthermore, as shown in Fig. 3, a contact 5 of each of the time releases has been included in the circuit for the signal control 75

relay SC. The remainder of the apparatus shown in Fig. 3 is similar in all respects to that shown in Fig. 2.

With the apparatus constructed as shown in Fig. 3, the operation of the apparatus when it is desired to permit a train to enter a siding is the same as the operation of the apparatus shown in Fig. 2. When it is desired to move a train out of a siding, however, it is necessary for the trainman to first open the door of the associated lock, and to then operate the associated time release TR. The operation of the time release interrupts at its contact 5 the circuit for the associated signal control relay SC, and thus causes signal 15 S^B to move to its stop position. The operation of the associated time release also prevents the associated relay E from picking up if a train is within less than braking distance of the section to the left of section B—C when the release is 20 set into operation, for the reason that the circuit for relay E will not become closed until after the time contact 6 of the release has become closed, and if the train is within less than braking distance of the section to the left of section B—C 25 when the release is set into operation, by the time the contact 6 has become closed, the train will have entered the section to the left of section B—C and will thus have caused track relay R^B to become deenergized and open the circuit 30 for the relay E. After the associated relay E has once become picked up, the remainder of the operation will be similar to that previously described in connection with Fig. 2 with the exception that after the train has entered section 35 B—C and the switch has been restored to its normal position, it is necessary for the trainman to restore the time release to its normal position to permit signal S^B to clear when the train subsequently passes out of section B—C.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a stretch of railway track divided into sections, a plurality of switches connected with one of said sections, a track circuit for said one section including a track relay, a signal for governing the entrance of traffic into said one section, a plurality of control relays one associated with each switch; a pickup circuit for each control relay including a manually operable contact, a front contact of said track relay and a back contact of each of the other control relays, an indication means controlled by each relay, and means for controlling said signal controlled by all of said relays.

2. In combination, two adjacent sections of railway track, a track circuit for each of said track sections including a track relay, a plurality of sidings connected with one of said sections by means of track switches, a control relay associated with each switch, a push button associated with each control relay, a time release associated with each switch, each said time release comprising first and second normally closed contacts which become opened immediately when the release is set into operation and a normally open contact which becomes closed at the expiration of a predetermined time interval after the release is set into operation; a 75 pickup circuit for each control relay including

the associated push button, a front contact of each of said track relays, and a back contact of each of the other control relays; a stick circuit for each control relay including its own front contact, a front contact of each of said track relays, and a back contact of each of the other control relays; first and second indication devices associated with each control relay, means for connecting each of said first indication devices in multiple with the associated control relay over the first normally closed contact of the associated time release, means for connecting each of said second indication devices in multiple with the associated control relay over the normally open contact of the associated time release, and a signal for controlling the entrance of traffic into said one section controlled by the track relay for the section, by each of said control relays, and by the second normally closed contact of each of said time releases. 20

3. In combination, two adjacent sections of railway track, a track circuit for each of said track sections including a track relay, a plurality of sidings connected with one of said sections by means of track switches, a control relay associated with each switch, a push button associated with each control relay, a time release associated with each switch, each said time release comprising first and second normally closed contacts which become opened immediately when the release is set into operation and a normally open contact which becomes closed at the expiration of a predetermined time interval after the release is set into operation; a pickup circuit for each control relay including the associated push button, a front contact of each of said track relays, and a back contact of each of the other control relays; a stick circuit for each control relay including its own front contact, a front contact of each of said track relays, and a back contact of each of the other control relays; first and second indication devices associated with each control relay, means for connecting each of said first indication devices in multiple with the associated control relay over the first normally closed contact of the associated time release, means for connecting each of said second indication devices in multiple with the associated control relay over the normally open contact of the associated time release, a plurality of contacts one operated by each of said switches and each arranged to be closed when and only when the associated switch occupies its normal position; a signal control relay, a circuit for said signal control relay including a front contact of the track relay for said one section, the second normally closed contact of each of said time releases, a back contact of each of said control relays, and said switch operated contacts; and a signal for governing the entrance of traffic into said one section controlled by said signal control relay. 30

4. In combination, a stretch of railway track including a plurality of switches, a signal adjacent one end of said stretch for governing traffic movements into said stretch in one direction, a relay associated with each switch, means for controlling each relay in such manner that the relay cannot be energized unless said stretch is unoccupied and the remaining relays are all de- 65 energized, and means controlled by said relays for controlling said signal.

5. In combination, a main section of railway track, a plurality of sidings connected with said main section by means of switches, a plurality 75

of subsections formed in said main section, one at each of said switches, means for connecting the rails of said section together on opposite sides of said subsections, a track circuit including a 5 track relay for said main section and for each of said subsections, a control relay associated with each switch; a pickup circuit for each control relay including a push button, a back contact of each of the other control relays, and a front 10 contact of the track relay for said main section; a stick circuit for each control relay including its own front contact, a back contact of each of the other control relays, and a front contact of the track relay for said main section, 15 and an electric lock for each switch controlled by the associated control relay and by the track relay for the associated subsection.

6. In combination, a main section of railway track, a plurality of sidings connected with said main section by means of switches, a plurality of subsections formed in said main section, one at each of said switches, means for connecting the rails of said section together on opposite sides of said subsections, a track circuit including a track 20 relay for said main section and for each of said subsections, a control relay associated with each switch; a pickup circuit for each control relay including a push button, a back contact of each of the other control relays, and a front contact of the track relay for said main section; a stick circuit for each control relay including its own front contact, a back contact of each of the other control relays, and a front contact of the track relay for said main section, 25 and an electric lock for each switch controlled by the associated control relay and by the track relay for the associated subsection and including the associated door operated contact, and a signal for said main section controlled by all of said relays and by all of said locks.

7. In combination, a main section of railway track, a plurality of sidings connected with said main section by means of switches, a plurality of subsections formed in said main section, one at each of said switches, means for connecting the rails of said section together on opposite sides of said subsections, a track circuit including a track relay for said main section and for each of said subsections, a control relay associated with each switch; a pickup circuit for each control relay including a push button, a back contact of each of the other control relays, and a front contact of the track relay for said main section; a stick circuit for each control relay including its own front contact, a back contact of each of the other control relays, and a front contact of the track relay for said main section, a lock for each switch provided with a manually operable lever for releasing the lock and with a magnet which must be energized to permit operation of the lock and with a contact which is open or closed according as the door which permits access to the lock lever is closed or open, means for controlling the magnet of each lock controlled by the associated control relay, and other means for controlling the magnet of each lock controlled by the track relay for the associated subsection and including the associated door operated contact.

8. In combination, a main section of railway track, a plurality of sidings connected with said

main section by means of switches, a plurality of subsections formed in said main section, one at each of said switches, means for connecting the rails of said section together on opposite sides of said subsections, a track circuit including a track 5 relay for said main section and for each of said subsections, a control relay associated with each switch; a pickup circuit for each control relay including a push button, a back contact of each of the other control relays, and a front contact of the track relay for said main section; a stick circuit for each control relay including its own front contact, a back contact of each of the other control relays, and a front contact of the track relay for said main section, a lock for each switch provided with a manually operable lever for releasing the lock and with a magnet which must be energized to permit operation of the lock and with a contact which is open or closed according as a door which permits access to the lock lever is closed or open, means for controlling the magnet of each lock controlled by the associated control relay, other means for controlling the magnet of each lock controlled by the track relay for the associated subsection and including the associated door operated contact, and a signal for said main section controlled by all of said relays and by all of said locks.

9. In combination, a main section of railway track, a plurality of sidings connected with said main section by means of switches, a plurality of subsections formed in said main section, one at each of said switches, means for connecting the rails of said section together on opposite sides of said subsections, a track circuit including a track relay for said main section and for each of said subsections, a control relay associated with each switch; a time release associated with each switch, each said time release being provided with a normally closed contact which becomes opened 40 as soon as the release is set into operation and with a normally open contact which becomes closed at the expiration of a predetermined time interval after the release is set into operation, a lock for each switch including a manually operable lever for releasing the lock, a magnet for preventing operation of the lever except when the magnet is energized and two door operated contacts which are closed or open according as a door which permits access to the lock lever is open 45 or closed; a pickup circuit for each control relay including one of the associated door contacts, the normally open contact of the associated time release, a back contact of each of the other control relays, and a front contact of the track relay for 50 said main section; a stick circuit for each control relay including its own front contact, a back contact of each of the other control relays and a front contact of the track relay for said main section; means for controlling the magnet of each lock controlled by the associated control relay, by the other door operated contact of the associated lock, and by the track relay of the associated subsection, and a signal for the main section controlled by the normally closed contact of each of 55 said time releases, by all said relays, and by all of said locks.

HARRY C. VANTASSEL,
